UNITED STATES PATENT OFFICE.

HENRY F. AUSTIN, OF NEW ORLEANS, LOUISIANA.

FEEDER FOR FOUNTAIN PENS.

Application filed July 14, 1921. Serial No. 484,761.

To all whom it may concern.

Be it known that I, HENRY F. AUSTIN, a citizen of the United States, residing at New Orleans, in the county of Orleans and State 5 of Louisiana, have invented a new and useful Feeder for Fountain Pens, of which the following is a specification.

The present invention relates to fountain pens or the like, the primary object of the 10 invention being to provide means for causing the ink contained in the ink sack, to flow to the pen point, thereby eliminating the necessity of the user throwing the pen in an endeavor to start the ink flowing.

15 Another object of the invention is to provide a device of this character which will be located at a point directly under the user's fingers so that the device may be readily and easily operated.

20 With the foregoing and other objects in view which will appear as the description proceeds, the invention resides in the combination and arrangement of parts and in the details of construction hereinafter described 25 and claimed, it being understood that changes in the precise embodiment of the invention herein disclosed, may be made within the scope of what is claimed, without departing from the spirit of the invention.

30 Referring to the drawing:—

Figure 1 is a plan view of a pen constructed in accordance with the present invention.

35 Figure 2 is a longitudinal sectional view through the pen barrel, and taken on line 2—2 of Fig. 1.

Figure 3 is a sectional view on line 3—3 of Figure 2.

40 Referring to the drawing in detail, the barrel of the pen is indicated by the reference character 5 in which is supported the usual rubber ink sack 6 which has one end thereof embracing a portion of the pen supporting member 7 through which the ink 45 passes in its travel to the pen point 8.

The barrel 5 is provided with an elongated opening 11 to accommodate the lever 9 which is pivotally supported between the walls of the opening, at a point intermediate its ends

as at 9', so that one end of the lever will 50 contact with the bar 10, when the thumb piece 11' is moved upwardly, thereby compressing the sack 6 to cause the same to fill with ink when the lever is released, it being understood however that the pen point 55 is positioned in a suitable ink container, prior to this operation.

The device forming the essence of this invention embodies a finger piece 12 which is formed on the forward end of the bar 10, 60 the finger piece being shown as provided with tapered walls cooperating with the tapered walls of the opening 13, formed in the barrel 5. The finger piece is of a construction to be engaged by the finger of the 65 user, to force the sack inwardly, and due to the construction of the walls of the opening and finger piece, it will be noted that the finger piece due to the curved walls thereof cannot become caught under the barrel when 70 depressed, but at all times remains in a position to be easily operated.

From the foregoing it will be seen that upon pressing the finger piece 12, ink within the sack 6 will be forced through the member 75 7 and into the pen point 8, to the end that the ink will flow rapidly to the pen point to facilitate the writing with the pen.

Having thus described the invention, what is claimed as new is:—

80 A fountain pen comprising a barrel, an ink containing sack positioned within the barrel, a relatively long bar disposed between the inner wall of the barrel and outer surface of the sack, a finger piece formed at one end 85 of the bar, said finger piece adapted to extend through the barrel, whereby the sack may be compressed, and means adapted to contact with the bar at a point substantially intermediate the ends thereof for compressing the sack.

In testimony that I claim the foregoing as my own, I have hereto affixed my signature in the presence of two witnesses.

HENRY F. AUSTIN.
